APPARATUS FOR STRIPPING INGOT MOLDS

David P. Anderson, Pittsburgh, Pa., assignor to
 The Alliance Machine Company, Alliance,
 Ohio, a corporation of Ohio

Application October 19, 1933, Serial No. 694,318

2 Claims. (Cl. 22—95)

- This invention relates to a novel apparatus for stripping ingot molds, and particularly to those that are known as being of the "big-end-up" type, although not limited thereto.
- 5 In the past, it has been customary in the vast majority of open-hearth steel plants to cast ingots in heavy, vertical, cast-iron molds, having a slight taper, with the smallest area adjacent the top, and which is open at both ends. When 10 "teeming" or pouring the ingot, the molds are placed on flat cast-iron plates or "stools" which are mounted on especially adapted ingot mold cars. After a "heat" or ladle full of steel is "teemed" into a row of molds, and the molten 15 metal has sufficiently solidified, a train of ingot mold cars, carrying the molds and ingots, is transported to an "ingot stripper" for removal of the mold, after which the ingots are charged into a soaking pit or reheating furnace.
- 20 The conventional "ingot stripper" is in the form of an electric overhead traveling crane under which are two or more pairs of parallel tracks, on one of which the train of loaded ingot mold cars is adapted to stand. On an adjoining track 25 a train of empty ingot mold cars carrying "stools" only is placed. The "stripping" mechanism depends from the overhead crane, and operates in such manner as to seize the molds by lugs cast on its side by means of a pair of links, lift them 30 vertically off of the ingot and place them on the empty stools on the ingot mold cars on the adjoining tracks.
- There have been several recent developments 35 in the form of ingots and molds which are calculated to improve the soundness of the metal of the ingots. One of these developments contemplates the reversal of the taper in the mold, making it what is now known as the "big-end-up" type. Another advance has been to provide a 40 refractory "hot-top" to provide a sink-head or "shrink-head" on top of the ingot.
- It is, of course, obvious to those skilled in the 45 art that the acceptance of the superior "big-end-up" mold has necessitated the provision of new methods and apparatus for stripping and handling the ingots and molds. Due to the small reduced end of the ingot, it can no longer stand unsupported for transportation to the soaking 50 unsupported for transportation to the soaking pit or reheating furnace after "stripping", as was the usual practice. It is not feasible to "up-end" ingots or lay them down upon their sides, as the metallurgical characteristics of the ingots would be badly affected.
- In view of the foregoing, it has become common 55 practice to loosen the ingot in the mold at
- the ingot stripper and to then leave it in the mold for transportation to the soaking pit, where it is withdrawn and charged into the furnace. The conventional soaking pit cranes are provided with tongs for lifting purposes only, and it is therefore necessary to convey the molds and ingots to the "stripper" for "feeling" the ingot, and to force loose what are known as "stickers".
- One object of the present invention is the provision of a novel apparatus for stripping ingots, 10 regardless of how tightly they may be "frozen" to the ingot mold.
- Another object is to provide a novel and inexpensive means for stripping ingot molds in a very rapid manner by the exertion of a camming 15 action on the top of the ingot mold, causing the ingot to move upwardly with respect thereto.
- A further object is to provide a novel apparatus of the class described which is simple in design and may be easily and cheaply manufactured and 20 used in conjunction with conventional types of lifting mechanism forming a part of standard mill equipment.
- The foregoing and still further objects will be apparent after referring to the drawings, in 25 which:
- Figure 1 is an elevation of the apparatus of the invention.
- Figure 2 is an enlarged elevation showing an ingot mold and part of the apparatus in section.
- Figure 3 is a fragmentary view similar to Figure 2 but showing the apparatus in another stage of operation.
- Figure 4 is a view similar to Figure 3 but showing the apparatus in still another stage of operation.
- Figure 5 is a sectional view on the line V—V of Figure 3.
- Referring more particularly to the drawings, the letters A indicate a pair of tracks on which 40 an overhead crane B is adapted to travel. A conventional overhead crane trolley C is adapted for movement on the crane B and supports a vertically disposed screw D and reels E and F. The screw D may be moved vertically with respect to the overhead trolley C by means of a motor G, while the reels E and F may be rotated by means of motors H and I, respectively.
- A pair of cables J is secured to the reel E while a similar pair of cables K is secured to the reels 50 F.
- A carriage 2 is supported by the cables J and K and comprises generally an extended sleeve to which there is pivoted, as at 3, a pair of hoisting links 4 having lug-engaging surfaces 5 on their 55

lower ends. The hoisting links 4 are moved about the pivots 3 by means of cables J and K, which are secured to the reels E and F.

The vertical screw D extends downwardly through the carriage 2 and has secured to its lowermost end a yoke 7 having connected to each of its ends a removable half-bearing 8 which is maintained in position by means of countersunk bolts 9 and nuts 10. A cam 12 is provided for each of the ends of the yoke 7 and each has a bearing surface 13 for frictional engagement with one of the bearings 8. The cams 12 are loosely pivoted to the ends of the yoke, as at 14, and have curved surfaces 15 adjacent their lower ends and gripping teeth 16 on their extremities.

An ingot mold 17, preferably corrugated, is provided with a lower portion 17^a of smaller area than the upper portion 17^b thereof, making it as 20 of the "big-end-up" type. Suitable lugs 18 are carried on the exterior of the ingot mold 17 for enabling its handling, and it is provided with a tapered aperture 19 extending through its bottom. A tapered plug 20 is disposed in the aperture 19 in such manner as to extend partially therethrough.

After molten metal has been "teemed" into the ingot mold 17 and the ingot solidified, as shown at 21, both mold and ingot are transported away from the "pouring" floor where it is desired to loosen them in order that they may be satisfactorily removed from the mold and placed in the usual soaking pit or reheating furnace.

According to the teaching of the present invention, the carriage 2 is lowered by means of the cables J and K in such manner as to enable the lug-engaging surfaces 5 of the hoisting links 4 to be in close proximity to the lugs 18, whereupon the reels E and F are adjusted relative to each other until the links are in lifting engagement. The carriage is then elevated, and the ingot mold 17 is rotated in such manner as to cause it to descend and lower the yoke 7, bringing the curved bearing surfaces 15 of the cams 12 in contact with the upper end of the ingot mold. The downward movement of the screw D is continuous, which causes the cams 12 to fulcrum with their surfaces 15 on the top of the ingot mold, and the teeth 16 to bite into the upper portion 50 of the ingot 21 at a point adjacent the base of the "hot-top", which has been previously removed. The teeth 16 on the cams 12 are curved as at 16^a, in order to conform with the corrugated indentations 21^a of the ingot.

55 Due to the fact that the cams 12 are loosely

pivoted, as at 14, their bearing surfaces 13 assume the thrust and impart it to the removable bearings 8, permitting the application of a tremendous force and the consequent positive upward movement of the ingot.

It is to be understood that the overhead crane trolley generally indicated at C forms no part of the present invention and may be one of any number of conventional types, and is merely disclosed herein as providing means for enabling the 10 operation of the apparatus of the invention, and while I have shown and described one specific embodiment of my invention it will be understood that I do not wish to be limited exactly thereto, since various modifications may be made 15 without departing from the scope of my invention, as defined in the following claims.

I claim:

1. Apparatus for stripping ingot molds comprising a carriage supported by an overhead crane, a pair of hoisting links pivoted to said carriage and adapted to be moved by said overhead crane, a vertically movable rod mounted on said carriage and adapted for relative movement with respect thereto, a yoke mounted on said 25 vertically movable rod, a removable bearing connected to each of the ends of said yoke, a cam pivoted to each of the ends of said yoke and having a bearing portion adapted to frictionally engage one of said removable bearings, said cams 30 having secondary bearing surfaces adapted to fulcrum on the top of said ingot mold, and means associated with each of said cams for gripping the metal of the ingot in such a manner as to cause it to move upwardly with respect to said 35 ingot mold when said cams are fulcrumed therein.

2. Apparatus for stripping ingot molds comprising a carriage supported by an overhead crane, a pair of hoisting links pivoted to said 40 carriage, a yoke adapted for vertical movement with respect to said carriage, said yoke being movable by said overhead crane, a freely-floating cam pivoted to each of the ends of said yoke, and means on said freely-floating cams for gripping the metal of the ingot, said cams being devoid of mechanical connection with said carriage and having surfaces adapted to fulcrum on the top of the ingot mold in such manner as to dispose said last named means in contact with the 50 ingot, whereby the ingot is caused to move upwardly with respect to said ingot mold solely by the fulcruming movement of said freely-floating cams.

DAVID P. ANDERSON. 55
